UNITED STATES PATENT OFFICE.

GEORGE H. BEIN, OF CLEVELAND, OHIO.

CAR STOP.

Application filed March 25, 1925. Serial No. 18,113.

To all whom it may concern:

Be it known that I, GEORGE H. BEIN, a citizen of the United States, residing at Cleveland, in the county of Cuyahoga and State of Ohio, have invented a certain new and useful Improvement in Car Stops, of which the following is a full, clear, and exact description, reference being had to the accompanying drawings.

10 This invention relates to stops for cars and is directed more particularly to a stop which is adapted to be fastened directly to the rails over which the car passes.

The primary object of the present invention is to provide a car stop which shall include a pair of members that are adapted to be fastened directly to the rails by means of clamp members and when so positioned, shall form an effective barrier for stopping 20 the cars.

Another object is to provide a car stop which may be fastened to the rails at points adjacent a wall or other obstruction, or which may be fastened at any desired point 25 along the rails.

A further object is to provide a car stop of this general character which shall be simple in construction, inexpensive to manufacture and which may be easily and quickly 30 applied to the railway track.

With these and other objects in view, the invention consists in the various novel features of construction and arrangement or combination, all of which will be fully described hereinafter and pointed out in the appended claims.

In the drawings forming part of this application, Fig. 1 is a side elevation of a section of track showing my improved car stop applied thereto; Fig. 2 is a top plan view thereof; Figs. 3 and 4 are transverse sectional views taken respectively on the lines 3-3 and 4-4 of Fig. 1; Fig. 5 is a perspective view of one of the clamp members for fastening the device to the railway track; and Fig. 6 is a perspective view of another type of clamp member used for fastening the device to a railway track.

Describing the various parts by reference 50 characters, 1 denotes the rails of a railway system to which the car stop is adapted to be attached. The car stop consists essentially of two stop members 3 which are preferably formed from steel, and these stop members are adapted to be clamped to the rails 1 in a manner to be described herein-

after. Each stop member is preferably formed with an end abutment 4, one face of which is provided with an arcuate portion 5 having a curve similar to the circumference of a car wheel which is adapted to abut thereagainst, as indicated by the dot-and-dash lines in Fig. 1. The arcuate portion 5 merges into a horizontal portion 6, the opposite end of which connects with an arcuate portion 7 having a curvature opposite to the portion 5. The arcuate portion 7 connects with an inclined surface 8 that extends downwardly to the level of the track at the end of the stop member 3.

Referring to Fig. 3, it will be noted that the end abutment 4 of each stop member is preferably widened as indicated at 10 and this widened portion is provided with a recess 11 which is adapted to receive the top and side of the rail 1 to which the member is attached. The horizontal portion 6 as well as the opposite end 8 of the stop member is adapted to contact with the top surface only of rail 1 and does not extend therebelow. Cooperating with the widened portion of the stop member is a clamping plate 12 which is adapted to contact with one face of the portion 10 and also engage with the opposite side of the rail 1. This plate 12 is held in position by any suitable fastening means such as bolts 13 which extend through the widened portion 10 and plate 12 above the rail, and also by bolts 14 which extend through the rail.

The opposite end of each stop member is clamped to the rail by means of a pair of interfitting clamp plates 16. As shown in Figs. 4 and 6, each clamp plate 16 is formed with a pair of spaced lugs 18 and 19 which are adapted to engage one beneath the head of the rail and the other over the top of such rail, the lug 19 projecting through an aperture 20 formed in the stop member. It will be noted that lug 19 is substantially one half the width of lug 18 so that when both clamps 16 are placed in position as shown in Fig. 4, the lugs 19 will be one alongside the other across the top of the rail. The upwardly projecting portion 23 of each of these clamp plates is adapted to seat within recesses 24 formed in the side wall of the stop member, and a bolt 25 and nut 26 serve to tie these parts together.

It will be understood that a stop member 110 as above described is fastened to each rail 1 at opposite points therealong and in order

to further strengthen the structure as a whole, I preferably tie the end abutments 4 together by means of a rod 28 which extends therethrough and is provided with a tubular spacing member 29 which contacts with the inner surface of each end abutment.

members having a recess adapted to receive the top and side of said rail, a clamping plate having a recess adapted to receive the opposite side of said rail, means for fastening said plate and member together about said rail, and a pair of interfitting clamp members connected to the opposite end of said rail, the clamp members being adapted to

In operation a car rolling along the tracks 1 will ride up the inclined portions 8 of the stop members and thus check the speed of the car to some extent. Continued movement of the car will permit the leading wheels to continue along the arcuate portion 7 and horizontal portion 6 and when such leading wheels near the arcuate portion 5 of the end abutment, the trailing wheels of the car will engage the inclines 8 of the stop members and thus serve to further check the speed of the car. Continued movement 20 of the car will cause the leading wheels to engage the arcuate portions 5 and bring the car to a complete stop. each of said stop members and adapted to closely embrace the head of its respective rail. 65 3. A car stop of the character set forth comprising a pair of stop members adapted to be fastened one to each rail of a railway track at opposite points, each stop member having at one end an arcuate portion 70 adapted to receive a car wheel and at the opposite end an inclined portion rising from the top of said rail, one end of each of said members having a recess adapted to receive the top and side of said rail, a 75 clamping plate having a recess adapted to receive the opposite side of said rail, means for fastening said plate and member to

A car stop constructed as above described may be fastened to the rails at any desired point and in view of the fact that the stop members are clamped to the rails by the plates 12, 16 and 17 it will be obvious that such stop members may be easily and quickly attached to the end of a track which abuts a wall or other obstruction.

4. A car stop of the character set forth

80

85

Having thus described my invention, what I claim is:

1. A car stop of the character set forth comprising a pair of stop members adapted to be fastened one to each rail of a railway track at opposite points, each stop member having at one end an arcuate portion adapted to receive a car wheel and at the opposite end an inclined portion rising from the top of said rail, one end of each of said members having a recess adapted to receive the top and side of said rail, a clamping plate having a recess adapted to receive the opposite side of said rail, means for fastening said plate and member together about said rail, and means for fastening the opposite end of each of said members to its respective rail.

2. A car stop of the character set forth comprising a pair of stop members adapted to be fastened one to each rail of a railway track at opposite points, each stop member having at one end an arcuate portion adapted to receive a car wheel and at the opposite end an inclined portion rising from the top of said rail, one end of each of said head of such rail, and a tie rod extending between said stop member, said tie rod having a spacing sleeve engaged thereover and interposed between said stop members.

In testimony whereof I hereunto affix my signature.

GEORGE H. BEIN.
